UNITED STATES PATENT OFFICE.

EDWARD FORBES O'NEILL, OF STORM LAKE, IOWA, ASSIGNOR TO HIMSELF
AND IRA D. CADY, OF SAME PLACE.

KEY-BOARD ATTACHMENT FOR MUSICAL INSTRUMENTS.

SPECIFICATION forming part of Letters Patent No. 299,492, dated May 27, 1884.

Application filed October 2, 1883. (No model.)

To all whom it may concern:

Be it known that I, EDWARD FORBES O'NEILL, of Storm Lake, in the county of Buena Vista and State of Iowa, have invented 5 a new and Improved Self-Playing Attachment for Key-Board Instruments, of which the following is a full, clear, and exact description.

The object of my invention is to provide a new and improved attachment for pianos, organs, and other key-board instruments, by means of which attachment persons not acquainted with music can play dances or any other kind of music on the instrument.

The invention, which is an improvement on 15 the self-playing attachment for key-board instruments for which United States Letters Patent No. 215,155 were issued to me on the 6th day of May, 1879, consists in the combination, with a series of false keys hinged to a strip, of 20 a frame adapted to rest on the said strip and the front of the instrument, which frame carries adjustable rollers and non-adjustable rollers over which an endless music band or belt passes, which is provided with projections. 25 One of the rollers is provided with friction-rings, whereby if the said roller is turned the sheet will be moved over the keys and the projections will depress the keys and false keys and produce the desired melody.

30 Reference is to be had to the accompanying drawings, forming part of this specification, in which similar letters of reference indicate corresponding parts in all the figures.

Figure 1 is a front view of a piano provided 35 with my improved attachment, parts of the same being broken out. Fig. 2 is a cross-sectional elevation of the same. Fig. 3 is a sectional plan view of the same. Fig. 4 is a plan view of some of the false keys. Fig. 5 is an 40 edge view of part of the chart, and Fig. 6 is a detail view.

A series of false keys, A, each provided at the front or outer end with a projection, A', on the bottom, are secured, by a piece, B, of 45 leather, cloth, or other flexible material, to a strip of wood, C, adapted to rest on the black keys D. The false keys A are so arranged that they can pass between the black keys D of the key-board, and by removing more or 50 less of the projections A' the false keys A can

be so adjusted that their upper surfaces will be flush with the upper surfaces of the black keys. A strip, E, having a longitudinal groove, E', in its top, is secured on the strip C, but does not extend to the ends of the same. 55 A strip, F, of leather, secured to the rear edge of the strip C, projects below the bottom surface of the same and passes in between the rear ends of the black keys D and the name-board F'. Two standards, G, are united at the top 60 by a longitudinal rod, H, and at the bottom of the standards there is a roller, J, one end of which revolves in an eye or an aperture in one standard and its other end in a slot extending to the bottom of the other standard, so that 65 the roller can be easily put in place and inside of the music-chair. The standards are also united at the rear ends of the bases by a rod, I, adapted to pass into and slide in the groove E' of the strip E. The standards G are provided 70 in the front edges with a series of notches, a, placed close together, and in the rear edges with three notches, b, spaced farther apart. A roller, K, rests loosely in notches a, and a roller, L, rests loosely in 75 notches b. A roller, M, has its ends passed through journal boxes or slides N, held to slide in vertical slots O in the standards G. At one end the roller M is provided with a crank-handle, P. Springs Q draw the slides N downward. 80 The roller M is surrounded by a series of projecting rubber rings, R. At the front a longitudinally-slotted leg, S, is held on the base of each standard by screws S' on the ends of a rod, s", passing across the front, which 85 rod serves to connect and help hold in place these legs and the standards, and which rod also serves as a hold for the left hand to keep the driver steady upon the instrument while turning the crank with the right hand. These 90 legs are provided with cushions o on the lower ends. An endless band or belt, T, is provided with a series of leather blocks, W, which are secured thereon parallel with each other and in such a manner as to depress the keys to 95 produce the desired melody. The ends of the blocks are beveled, and the blocks are made longer or shorter, as may be necessary. The rubber rings R are so arranged that they come in contact with the endless band T between 100

the blocks W, and the said blocks are so arranged that they will strike the black keys D or the false keys A. The name of the piece of music and the words are printed on a blank space, Y, on the band or belt T.

The operation is as follows: The endless belt or band T is passed over the rollers K L and under the rollers J M in the manner shown in Fig. 2, and the rollers K and L are so adjusted to the notches a and b according to the greater or less length of the belt or band. The roller M is drawn downward by the springs Q and holds the belt or band T taut. The strip C is placed on the rear or inner ends of the black keys D, and the wire I is placed in the groove E'. The legs S are then adjusted to rest on the front rail of the casing and to hold the standards vertically. By turning the crank-handle P the endless band will be moved over the keys by the rubber rings R, which produce sufficient friction to move the belt or band. The projections W depress the keys, and thereby the desired melody will be produced. The attachment can be placed on a piano very easily or removed from the same. If the false keys are depressed, they depress the white keys.

Having thus described my invention, what I claim as new, and desire to secure by Letters Patent, is—

1. The combination, with a series of false

keys hinged to a strip and adapted to pass between the black keys of a key-board, of a frame resting partly on the strip to which the false keys are hinged, and of an endless music belt or band held on the frame which is provided with means for moving the belt or band, substantially as herein shown and described.

2. The combination, with the strip C, the false keys A, the grooved strip E, the standards G, and the rod I, fitting in the grooved strip E, of means for passing an endless music belt or band provided with projections over the keys, substantially as herein shown and described.

3. The combination, with the strip C, the false keys A, the grooved strip E, the standards G, the rod I, fitting in the groove in the strip E, and the adjustable front legs, S, of means for passing an endless music belt or band provided with projections over the keys, substantially as herein shown and described.

4. The combination, with the standards G, of the adjustable rollers K and L, the roller J, the roller M, provided with friction-rings R, the slides N, the springs Q, and an endless band or belt provided with projections W, substantially as herein shown and described.

EDWARD FORBES O'NEILL.
